UNITED STATES PATENT OFFICE.

EVERETT GOLDSWAIFT, OF ELKHART, INDIANA.

COIN-CONTROLLED BRUSHING-MACHINE.

No. 880,276.

Specification of Letters Patent.

Patented March 8, 1908.

Application filed January 15, 1906. Serial No. 296,022.

To all whom it may concern:

Be it known that I, EVERETT GOLDSWAIFT, a citizen of the United States of America, and a resident of Elkhart, in the county of Elkhart and State of Indiana, have invented certain new and useful Improvements in Coin-Controlled Brushing-Machines, of which the following is a specification.

My invention relates to brushing machines and has for its object improvements in devices of that kind.

More particularly my invention intends to provide a power driven brush which may be started into operation by means of a coin, and which after having run a certain predetermined length of time will automatically come to a stop.

In the accompanying drawings Figure 1 is a side elevation with part of the casing 20 broken away so as to expose the inner working mechanism; Fig. 2 is an enlarged elevation of the coin-actuated contact springs and their associated parts; Fig. 3 is a section on line 5—5 of Fig. 4; Fig. 4 is an elevation of 25 the wheel which controls the electrical circuit after a coin has been deposited in the machine; and Fig. 5 is a diagram of the electrical circuits used.

In the accompanying drawings A is a base 30 plate upon which is mounted a casing B for enclosing the operating mechanism. This casing is made in two halves, being divided longitudinally and so arranged that the coin chute extends through one of the halves and 35 may be connected to the inner mechanism before the other half is secured in place. Secured at a convenient place on the base plate A is a motor M which is connected by gears M¹ to a shaft M² supported in standards 40 C. The shaft M² extends through an opening in the front part of the casing B and carries on its end a brush D. When the motor is set into operation it causes a rotation of the brush. A shield B¹ over the brush D 45 serves to both protect the brush and also to secure the two halves of the casing B together at their upper parts. A pair of gears E connect the shaft M² to a worm shaft F which engages a worm gear not shown. The 50 shaft F¹, which carries the worm gear, has on its outer end a metal disk H which is provided with a notch H¹. This disk runs between two insulated contact springs J. These 55 springs each have two contact points J¹ and J² at which they engage the disk H. The points J¹ engage the disk near its periphery

and make electrical connection therewith. The points J² engage insulating surfaces H² on the disk H and consequently do not make electrical connection.

The casing B is provided with bosses B² into which are screwed pipes K, which, with cross pipes K¹, form a standard rising from the machine. The cap at the top of the pipe is provided with a coin slot, and from this slot a coin chute L extends down through the pipe K to a block L¹ within the machine and directly over the disk H. It is this block which serves as a support for the insulated springs J.

Supported at a convenient place, as on one of the standards C, is a magnet P provided with an armature lever P¹ arranged to close a circuit at P² for the motor M whenever the magnet P is actuated. A spring P³ acts to 75 break the circuit for the motor when a current ceases to flow through the magnet P. The manner in which the electrical parts are arranged is shown in the diagram of Fig. 5, in which Q are two binding posts secured at any 80 place to the machine, R a resistance, and P a coin to close electrical connections between the springs J. These parts, excepting the coin, are connected to previously described parts by wires as shown. The posts Q are 85 connected to any convenient source of electricity.

In normal position the disk H has its notch H¹ in line between the springs J so that these springs are not in electrical connection with each other. In this condition a coin is dropped through the chute L and drops into the notch H¹ between the springs J thereby placing these springs in electrical connection with each other through the coin. A current 95 of electricity then flows from the source to a post Q, thence through the resistance R to one spring J, through the coin to the other spring, and thence through the magnet P and the other post Q back to the source. This 100 actuates the magnet P and causes its armature P¹ to close a branch connection through the motor M at the point P². When this occurs the motor starts into operation. The 105 operation of the motor causes a rotation of the shaft M² and the brush D, against which brush the patron of the machine may press his shoe to have it cleaned.

From the shaft M² motion is communicated through the gearing described to the 110 disk H causing its rotation. The movement of the disk pushes the coin to one side from

- between the springs J and permits it to fall into a coin receptacle beneath the disk H. As the coin is being pushed from between the springs J the body of the disk takes its place as the means of completing and maintaining 5 the electrical circuit through the magnet P. This condition continues until the motor has run long enough to cause the notch H¹ in the disk H to come again to the springs J. When this occurs the circuit is broken through the magnet P, and this in turn permits the spring P² to move the armature P¹ so as to break the electrical connections for the motor at P². This brings the mechanism to a stop with 15 the disk H so located that the notch H¹ is between the springs J. As before described, this is the normal position and one in which the machine is ready for the reception of another coin.
- 20 The motor is one of the ordinary kind which runs at or near a certain definite number of revolutions per minute. The disk H and its coöperating parts are so arranged that upon the disk making one complete 25 rotation, after being started, the mechanism comes automatically to a stop. And the gearing between the motor and the disk is so arranged that the motor will make some predetermined number of revolutions to one 30 rotation of the disk. As a consequence, the result of dropping a coin into the opening at the top of one of the standards or pipes K is to cause the brush D to be rapidly rotated for some predetermined period of time.
- 35 What I claim is:—
1. In a brushing machine, the combination with a motor, of a coin chute, a disk at the inner end of the coin chute and provided with a notch for receiving a coin placed 40 within said chute, an electrical connection closed by a coin when within said notch, means by which the closing of said electrical connection will cause the motor to start into operation, and connections from the motor 45 to the disk for causing the rotation of the latter to remove the coin from its position for making said electrical connection, said disk and said electrical connection being so arranged that the disk will hold the electrical 50 connection closed after the coin is removed but will permit the breaking of said connection upon a predetermined movement of said motor.
  2. In a brushing machine, the combination with a motor, of a casing containing the motor, a standard consisting of a pipe extending upward from the top of the casing and having a coin slot at its upper end, a coin chute within said pipe and extending to 55 the interior of the casing, a notched disk within the casing and arranged to receive and support a coin passing through said chute, contact springs placed in electrical connection with each other by a coin so supported, means by which the electrical con- 60
  - nection so closed will cause the motor to be started into operation, and connections from the motor to the disk for causing a movement of the latter to remove the coin from its contact closing position. 70
  3. In a brushing machine, the combination with a motor, coin operated devices, and an inclosing case, of a standard formed of pipes and rising from the upper part of said case, and a coin chute extending through one 75 of said pipes to the coin operated devices in the interior of said case.
  4. In a brushing machine, the combination with a motor, of a chute through which a coin may be deposited within the machine, a 80 disk provided with a notch adapted to receive a coin so deposited, contact springs on each side of said notch and arranged to be electrically connected to each other through a coin resting in said notch, means by which 85 the closing of such electrical connection will set the motor into operation, and connections from the motor to the disk for rotating the latter so as to remove the coin from between said springs. 90
  5. In a brushing machine, the combination with a motor and an inclosing case, of a coin chute extending to the interior of the case, a notched disk within the case and arranged to receive and support a coin passing 95 through said chute, contact springs placed in electrical connection with each other by a coin so supported, means by which the electrical connection so closed will cause the motor to be started into operation, and connections from the motor to the disk for causing a 100 movement of the latter to remove the coin from its contact closing position. 100
  6. In a brushing machine, the combination with a motor, a magnet for starting it 105 into operation, and a normally open circuit for said magnet and arranged to be closed by a coin deposited within said machine, of a rotatable device arranged to primarily hold a deposited coin in a position to close said circuit, and connections from the motor to the 110 rotatable device for rotating it so as to remove the coin from its circuit-closing position, said rotatable device being so arranged that it will hold the circuit closed after the 115 coin is removed. 110
  7. In a brushing machine, the combination with a motor, and a magnet for starting it into operation, of a circuit for said magnet primarily controlled by a coin placed within 120 the machine, a disk provided with a notch serving to guide such coin into a circuit-closing position, and connections from said motor to said disk for rotating it, said parts being so arranged that the rotation of said disk 125 serves primarily to remove the coin from its circuit-closing position and secondarily to control said circuit after such removal. 130
  8. The combination with a motor, an electrical connection for the motor, and a coin 135

- chute, of means by which a coin deposited in said chute will cause the closure of the circuit for the motor, and devices for removing the coin from the position in which it causes the closure of the circuit immediately after the starting of the motor, said coin removing devices being so arranged as to hold the electrical connection closed after the removal of the coin.
9. The combination with a motor, an electrical connection, and a coin chute, of means by which a coin placed in said chute closes said circuit, and means for removing the coin from its circuit closing position, said coin removing means serving also to hold the circuit closed after the removal of the coin.
10. The combination with a motor, and a coin chute, of a disk located at the end of the chute and provided with a notch adapted to receive a coin, a pair of contact springs located on opposite sides of the disk but not normally in electrical connection therewith, an electric circuit connected to said springs and normally open thereat, said springs being so located that a coin deposited in said notch closes the electrical connection between said springs, and means by which said motor is started into operation upon the closure of said connection.
11. The combination with a motor, of a circuit for said motor, means by which the circuit for said motor will be closed upon depositing a coin within a chute, a chute for receiving the coin, and means controlled by the motor for removing the coin from the position in which it causes such closure of the circuit, said coin removing means serving also to hold the circuit closed after the removal of the coin and until the motor has made a predetermined number of revolutions.

Signed at Elkhart, Ind., this 10th day of January 1906.

EVERETT GOLDTHWAIT.
